UNITED STATES PATENT OFFICE.

WILLIAM H. STOUT, OF BROOKLYN, NEW YORK.

MANICURE-FILE.

1,175,388.

Specification of Letters Patent. Patented Mar. 14, 1916.

Application filed April 1, 1915. Serial No. 18,460.

To all whom it may concern:

Be it known that I, WILLIAM H. STOUT, a citizen of the United States, residing at Brooklyn, in the county of Kings and State 5 of New York, have invented certain new and useful Improvements in Manicure-Files, of which the following is a full, clear, and exact description, such as will enable others skilled in the art to which it appertains to 10 make and use the same.

My present invention relates to manicure files, and has for its object to produce such a file, as an article of manufacture, which will obviate some of the disadvantages 15 of the present constructions. As commonly constructed, such files have metallic tips and handles, although sometimes tips of other substances are attached as separate structures to the files. A metallic tip has the 20 disadvantage of scratching the under surface of the nail, and manicure experts prefer to use soft substances there so as to avoid thickening the nail, a tendency which is well known where metal is used. Also 25 the handles commonly employed become rusty and soil the hands or may even, under some conditions, spread infection. To obviate these troubles, I apply to the file, on the tip and on the handle, a thin coating of 30 some non-metallic, non-oxidizable substance. That which I prefer is celluloid. As the tip is tapering, such a coating may be pulled off unless securely attached, and to prevent this, I roughen the tip, preferably by 35 extending the first cut of the file all the way to the end thereof.

The accompanying drawing shows an embodiment of my invention wherein—

Figure 1 is a perspective view of my improved file; Fig. 2 is a section on the line 40 2—2 of Fig. 1; and Fig. 3 is a section on the line 3—3 of Fig. 1.

A is the metallic portion of the file, of which B is the handle, and C is the tip. 45 In Fig. 2 it will be observed that the portion C carries teeth c indicating that the first cut of the file has been carried to the end of

the tip thereof, while in Fig. 3 no such construction is necessary because, as will be observed, this end of the file is larger than 50 the body so that the coating easily keeps its place, in addition to which the notch B² prevents the coating coming off. The coating is indicated at C¹ in Fig. 2, and at B¹ in Fig. 3. 55

I prefer celluloid for the coating because this is cheap and is easily applied. It may be applied in any way not inconsistent with the invention, but it is intended in producing the file to keep it of substantially uniform thickness throughout, and while this may be accomplished by attaching the celluloid in sheets, it is most readily effected by dipping the file to suitable depth in a solution of celluloid and allowing the latter to 60 harden. When the files are properly cleaned so that no grease or dirt is upon the metal, the celluloid becomes very closely adherent. In general I prefer to apply two coats, permitting one coat to dry for some time before 65 the second is applied. 70

Having described my invention, what I claim as new and desire to secure by Letters Patent is:

1. As a new article of manufacture, a 75 manicure nail file having a closely adherent non-metallic coating applied to one or more ends thereof.

2. As a new article of manufacture, a manicure nail file having one or more ends 80 covered with a thin, closely adherent, coating of celluloid.

3. As a new article of manufacture, a manicure nail file having the tip roughened by extending the first cut of the file there- 85 over and covered with a closely adherent thin coating of celluloid.

In testimony whereof I affix my signature, in the presence of two witnesses.

WILLIAM H. STOUT.
